Nathaniel K. Fedde(57) **CLAIM**

The ornamental design for a store module, as shown and described.

DESCRIPTION

FIG. 1 is a front elevation of a store module, showing my new design.

FIG. 2 is a left side elevation view thereof.

FIG. 3 is a right side elevation view thereof.

FIG. 4 is a rear elevation view thereof.

FIG. 5 is a front upper right perspective view thereof.

FIG. 6 is a front upper left perspective view thereof.

FIG. 7 is a rear upper right perspective view thereof; and, FIG. 8 is a rear upper left perspective view thereof.

The broken lines are illustrations of unclaimed environmental structure.

The line shading and stippling show contour and not surface ornamentation.
